UNITED STATES PATENT OFFICE.

JOHN T. WILCOX, OF PONTIAC, MICHIGAN, ASSIGNOR TO OAKLAND MOTOR CAR COMPANY, OF PONTIAC, MICHIGAN, A CORPORATION OF MICHIGAN.

SEAT-SPRING.

1,084,917.

Specification of Letters Patent.

Patented Jan. 20, 1914.

Application filed June 12, 1913. Serial No. 773,334.

To all whom it may concern:

Be it known that I, JOHN T. WILCOX, a citizen of the United States, residing at Pontiac, county of Oakland, State of Michigan, have invented a certain new and useful Improvement in Seat-Springs, and declare the following to be a full, clear, and exact description of the same, such as will enable others skilled in the art to which it pertains to make and use the same, reference being had to the accompanying drawings, which form a part of this specification.

This invention relates to vehicle seat springs and has for its object spring structure which in its entirety forms an efficient and durable seat for yieldingly supporting people. The superior efficiency is due to a peculiar method of tightening the helical springs together at their free ends. The peculiar durability is due to the method of attaching the band springs which form the supporters of the upholstering at the edges.

Still another feature of my invention is the means by which the helical springs are held to the stationary frame of the spring structure.

In the drawings: Figure 1, is a fragmentary plan view of the spring structure. Fig. 2, is a vertical cross section. Fig. 3, is an enlarged detail of the cross wires in attached relation with the upper coils of the helical springs. Fig. 4, is a detail of one of the rear helical springs and parts of the movable and stationary frames, showing the hinging action of the band spring. Fig. 5, is a detail of one of the helical springs showing how it is attached at one end.

The spring structure comprises essentially two frames, the lower frame *a* and the upper frame *b*. To avoid relative terms the upper frame will be designated as the movable frame and the lower frame will be designated as the stationary frame. The stationary frame *a* is a rectangular wooden frame. Strips of sheet metal or channel strips *c* cross the stationary frame widthwise and act as holders of the helical springs. These channel strips are bent over the end coil of each helical spring in the row, that is, the edges *d*, which, before the insertion of the end coils, are upright, are turned over against the wire of the end coils. The peculiar feature of this clamp is the raised center portion or longitudinal corrugation *e* of the channel strip. This causes the end

coils of the helical springs to be bent to a sort of V shape when viewed sidewise, as shown in Fig. 5, so that they cannot shift sidewise in the channel strip in case the end coil does not exactly fit the interior of the channel strip. Lengthwise movement in the channel strip is prevented by the turned-over edges or lips *d*. The result is that by this simple arrangement the spring is securely located at the point desired. The ease with which the springs may be attached to the stationary frame is one feature of this method as well as the security.

The helical springs *f* support on their free ends (that is the movable ends) the movable frame *b*. This movable frame comprises a border member, which is preferably constructed of stiff wire *g*. The adjacent end coils of the helical springs are connected with the border wire by the aid of cross wires which exist in two sets that run at right angles to each other. One set, for the purpose of clearness, will be designated the stringer wires or stringer members and the other set will be designated the interlocking wires. The cross wires *h* are interlocking wires and the lengthwise wires *i* are the stringer wires or stringer members. The stringer wires or stringer members *i* are coiled about the border wire *g* at one side of the frame and extend to the opposite side over the end coils of the helical springs. They are fastened to the opposite side of the frame by coiling around the border wire.

The interlocking wires *h* are similarly coiled about the border wire *g* and extend to the opposite side of the frame where they are again coiled about the border wire to fasten them thereto, but instead of lying across the top of the helical springs, the wire first passes across the free-end coil of the helical spring (Fig. 3) then passes under this coil, thence over the stringer member *i*, thence again under the free-end coil and thence over the same and continues on to the next helical spring. This forms a very secure attachment for the helical springs at their free ends; for, if one of the helical springs is subjected to a compression strain, the wires will draw together with more tightness in much the same fashion that some knots will when a pulling effort is exercised on the line. This is considered an improvement over the different forms of attachment that have heretofore been used,

such as clips of wire, metal or the like, which, when subjected to such a strain, tend to slide across one of the cross members rather than to tighten their engagement. This tightening of the attachment so as to afford a good draft connection between the spring directly subjected to strain and its neighbors, is quite important in seat-spring structure. With the seat-springs it is advantageous to have some of the strain communicated and taken by adjacent springs, as the yielding action must be stiffer in order to support the weight of the occupants. To this end I have designed this self-tightening interlock so that tight draft members will draw on the neighboring springs when one spring is subjected to compression. Not the least feature of this form of tight interlock is its simplicity, it being merely a weaving together of the cross members that form the support for the upholstering. Coöoperating with these cross members and supporting the upholstering of the seat are a plurality of band springs *j* which are constructed of clock spring steel. These not only prevent the upholstering from protruding through the movable spring frame, but also act as edge springs to give a yieldability to the upholstering at the edge of the seat and yet I prevent it being forced between the movable and the stationary frame. One end of the band spring *j* is nailed to the wooden bar of the stationary frame *a* by the same nail *k* which attaches the channel strip *c*. The band spring bows out, as shown in Fig. 2 and then crosses the movable frame by going over the border wire *d* and under the stringer members *u*. The other end of the band spring is connected with the border wire *g* at the opposite side of the movable frame by means of a two-way hinging device, which comprises a clip *l* that is riveted to the end of the band spring, as shown in Fig. 1. This allows the band spring to move on the rivet in relation to the clip as shown by the upper fragmentary band spring of Fig. 1, and, in view of the clip engaging loosely about the border wire *g*, it allows the band spring to move in a vertical plane, as shown in Fig. 4. This double hinging action provides for all movements of the band spring relatively to the stiff part of the movable frame without resulting in any torsional or tensile strains that would tend to tear the parts.

I am aware that band springs have been

used in connection with spring structures for edge supports, but I do not believe that they have ever been connected with the rigid portion of the movable frame in the manner that I propose, to avoid the torsional and tensile strains already alluded to. The avoidance of these strains is not the only advantage of my method of attachment, but it gives a larger flexibility to the spring than would be secured by merely coiling the band spring about the stiff border wire in the fashion that has been done in the past. 70

What I claim is:—

1. A spring construction, having in combination, a stationary frame, a movable frame, helical springs connecting the two frames and band springs attached to the stationary frame bowed out at the edge of the spring structure, thence crossing the movable frame and slidably attached thereto and having a hinging connection with the opposite side of the movable frame, substantially as described. 75

2. A spring construction, having in combination, a stationary frame, a movable frame, helical springs connecting the two frames and band springs attached to the stationary frame, bowed out at the edge of the spring structure, crossing the movable frame and slidably attached thereto and having a two-way hinging connection with the opposite side of the movable frame, substantially as described. 80

3. A spring construction, having in combination, a stationary frame, a movable frame provided with a stiff border wire, helical springs connecting the two frames, band springs attached to the stationary frame, bowed out at one of the edges of the spring structure, thence crossing the stationary frame and slidably attached thereto and clips rotatably engaging about the stiff border wire of the movable frame, and loosely riveted to the adjacent ends of the band springs by rivets parallel with the axis of the helical springs to give the band springs a two-way hinging movement with respect to the border wire, substantially as described. 95 100 105

In testimony whereof, I sign this specification in the presence of two witnesses.

JOHN T. WILCOX.
